UNITED STATES PATENT OFFICE.

HAYWARD O. BAIR, OF COLVILLE, WASHINGTON.

BED-CORNER LOCK.

1,068,095.

Specification of Letters Patent.

Patented July 22, 1913.

Application filed March 18, 1913. Serial No. 755,124.

To all whom it may concern:

Be it known that I, HAYWARD O. BAIR, a citizen of the United States of America, residing at Colville, in the county of Stevens and State of Washington, have invented certain new and useful Improvements in Bed-Corner Locks, of which the following is a specification.

This invention relates to corner locks for metal bedsteads and one of the principal objects of the invention is to provide reliable and efficient means for connecting the side rails of a bedstead to the corner posts.

Another object of the invention is to provide a corner lock comprising two sheet steel plates, one of which is provided with a series of openings and detachably secured to the bed post, and the other member comprises a plate having a series of tongues to fit the openings in the other plate.

Still another object of the invention is to provide a corner lock for bedsteads in which the plate secured to the post may be readily detached and shipped separately and to avoid injury to the post or plate.

These and other objects may be attained by means of the construction illustrated in the accompanying drawing, in which:

Figure 1 is a side elevation of one end of the side rail of a metal bedstead and showing one member of my corner lock secured thereto; Fig. 2 is a similar view of a bed post having the lock member secured thereto; Fig. 3 is a side elevation of a portion of a corner post showing the key hole slots for detachably securing the lock member in place; Fig. 4 is a horizontal sectional view of the post and the lock member secured thereto; Fig. 5 is an end elevation of the side rail showing the tongue plate secured thereto.

Referring to the drawing, the numeral 1 designates a tubular corner post of a metal bedstead and 2 is the side rail. These parts of the bedstead may be of the usual or any suitable type and the bed post is provided with a plurality of key hole slots 3.

The plate 4, preferably formed of sheet steel, is provided with an inwardly turned flange 5 at its edge and two rectangular openings 6 extending through the plate. It will be seen on reference to Fig. 2 that these

openings are slightly inclined from the vertical for a purpose which will presently appear. Extending through the plate 4 is a plurality of bolts 7 provided with polygonal nuts 8 and an integral head 9. The heads 9 of the bolts are placed in the larger portions of the key holes 3 and when depressed, the shank portions 7 of the bolts extend through the contracted portion 10 of the key hole slots, after which the nuts 8 are tightened up to hold the plate firmly to the bed post and to permit its ready detachment when desired for shipping or storing.

The side rail 2 has attached to its ends a flat sheet steel plate 11 provided with a plurality of tongues 12 cut from the body of the plate and bent outward as shown in Fig. 5. This plate is secured to the side rail by means of rivets 13. To secure the side rail to the post, the tongues 12 are inserted in the openings 5 and when the side rail 2 is pushed down until the flange 14 on the side rail bears against the upper edge of the plate 4 and the flange 5, the two parts are firmly connected together and cannot become accidentally detached. By raising the side rail 2, it may be quickly detached from the plate 4. Owing to the inclined disposition of the openings 6, the tongues 12 will bind tightly against the plate and hold the two parts firmly connected.

From the foregoing, it will be obvious that my corner lock is simple in construction, being made from sheet steel, can be readily connected to any metal bed post and side rail, is inexpensive to manufacture, and the plate connected to the post can be quickly detached when desired, thus facilitating the shipping of the parts. It will also be obvious that the two members of the lock may be connected to any form of metal post and side rail without modification.

I claim:

The herein described corner lock for bed posts comprising a tubular post provided with key-hole slots communicating with the interior thereof, said slots being disposed with their smaller branches downward, a plate provided with rectangular openings therein, an angular flange at one edge and headed bolts adapted to extend through the plate and into the key-hole slots of the post

for holding said plate in position, said rectangular openings being inclined relatively to the flange and a side rail provided with a plate having a plurality of downwardly extending tongues cut and bent from the body of the plate to extend through said openings and lock the side rail to the post.

In testimony whereof I affix my signature in presence of two witnesses.

HAYWARD O. BAIR.
